UNITED STATES PATENT OFFICE.

JOHN B. ODELL, OF CHICAGO, ILLINOIS.

ELECTRICAL SWITCH-BOARD.

SPECIFICATION forming part of Letters Patent No. 252,395, dated January 17, 1882.

Application filed July 29, 1881. (No model.)

To all whom it may concern:

Be it known that I, JOHN B. ODELL, of Chicago, Cook county, Illinois, have invented certain new and useful Improvements in Switch-Boards, of which the following is a specification.

My invention relates to improvements in that class of switch-boards for telegraph-lines in which the wires to be connected are attached to metallic strips arranged at right angles to each other. Such boards are usually secured to the wall in a vertical position, and difficulty heretofore has been experienced in keeping the switch-plug in place to properly form the connection between the strips, especially where the telegraph-station is situated near a railroad-track, as the jarring caused by the passage of trains tends to loosen and disengage the locking devices which heretofore have been employed to keep the plug in place.

The object of the present invention is to provide a cheap, simple, and efficient means of keeping the plug in place, which will not interfere with ease and facility in applying and removing it to and from the board; and to this end my invention consists in providing the strips with countersunk threaded holes for the insertion of the plug, the holes in the outer strips being larger than those in the inner strips, and providing the plug with shoulders and screw-threads adapted to fit in said holes, the shoulders on the plug being the same distance apart as the strips, so that the plugs will all fit alike, and, being screwed into both strips, tend to hold the same rigid, and prevent vibration or rattling.

In practice I find that if the threads be cut to tighten the plug by a three-quarters turn thereof, it will be sufficient to retain the same in place with certainty. It is to be observed that though the thread at the end of the plug is on a smaller screw, it should be cut at about the same pitch as the other thread, so as to bring both shoulders to bear against the strips at the same time.

In the accompanying drawings, which form a part of this specification, Figure 1 is a perspective view of a device embodying my invention, and Fig. 2 is a section on line xx of Fig. 1.

In the drawings similar letters of reference indicate like parts.

A represents the frame or cross-pieces of the switch-board, to which the outer metallic strips, B, are secured by screws or otherwise on one side, and the inner strips, C, on the other side, the latter being arranged at right angles to the former.

D D are the binding-posts, by which the wires are connected with the strips. The strips B are provided with threaded holes b and the strips C with smaller threaded holes c , the one immediately opposite the other. The holes are preferably countersunk or made flaring, as shown at b' and c' , to facilitate the entrance of the plug H. The plug H is provided with shoulders h and screw-threads h^2 h^3 , adapted to fit in the corresponding holes in the strips B and C.

H' is the handle of the plug, preferably made of vulcanite or other insulating material. The tip end of the plug is made enough smaller than the other end to pass readily through the threaded holes in the outer strip, B.

Switch-boards may be constructed in this way with any number of strips and cross-strips.

It is obvious that the strips B and C may, if preferred, be arranged parallel to each other; but I consider the arrangement shown the best.

I am aware that switch-boards have heretofore been made having plugs secured to one of the bars thereof by a bayonet catch, as shown in the patent to C. S. Jones, No. 90,270, dated May 18, 1869, and also having plugs secured to one of the cross-bars by screw-threads, as shown in the patent to E. T. Quimby, No. 244,143, dated July 12, 1881, and I hereby disclaim such constructions.

I claim—

In a switch-board, the combination of strips B, provided with threaded holes b , and cross-strips C, provided with smaller threaded holes c , and plug H, provided with screw-threads h^2 and h^3 , adapted to fit in the corresponding holes in said strips and cross-strips, substantially as specified.

JOHN B. ODELL.
